UNITED STATES PATENT OFFICE.

JOHN LEVINE, OF DETROIT, MICHIGAN.

NEWSPAPER-VENDING MACHINE.

1,274,724.

Specification of Letters Patent.

Patented Aug. 6, 1918.

Application filed August 25, 1917. Serial No. 188,111.

To all whom it may concern:

Be it known that I, JOHN LEVINE, a citizen of the United States of America, residing at Detroit, in the county of Wayne and 5 State of Michigan, have invented certain new and useful Improvements in Newspaper-Vending Machines, of which the following is a specification, reference being had therein to the accompanying drawings.

10 This invention relates to a newspaper vending machine, although the machine, with or without slight modifications and changes, may be used for vending other articles, such as books, magazines and various 15 kinds of periodicals.

The primary object of my invention is to provide a machine of the above type which may be easily and quickly loaded and used on street corners and at other prominent 20 places for dispensing daily newspapers in lieu of a news boy, the machine being constructed so that there may be newspapers for a great many subscribers, and it is in this connection that the machine and its 25 controlling mechanism may be considered a combination of a plurality of individual machines, within one structure and having a common coin magazine and certain other features for the benefit of subscribers and 30 the owner.

A further object of my invention is to provide a machine of the above type wherein the parts are constructed with a view of reducing the cost of manufacture, and at the 35 same time retain those features by which durability, ease of operation and safety of the papers or merchandise are secured. With such ends in view, my invention resides in the novel construction, combination 40 and arrangement of parts to be hereinafter specifically described and then claimed.

Reference will now be had to the drawing, wherein—

Figure 1 is a vertical longitudinal sectional view of a portion of the machine, looking at the inner side of the front wall of the machine to show the coin controlled operating mechanism relative to the dispensing compartments of the machine;

50 Fig. 2 is a horizontal sectional view of a portion of the machine;

Fig. 3 is an enlarged vertical sectional view of a portion of the coin controlled operating mechanism;

Fig. 4 is a similar view, showing a portion of one of the door latches;

Fig. 5 is a front elevation of the machine.

In describing my invention by aid of the views above referred to, I desire to point out that the same are intended as merely illustrative of an example by which my invention may be put into practice, and I do not care to confine myself to the precise construction and arrangement of parts shown. The following description is therefore broadly construed as including such substitute constructions and arrangement of parts which are the obvious equivalents of those to be hereinafter referred to.

The machine, as shown, is made of light 70 and durable metal and such parts of the machine as exposed to the elements are finished so as to be non-corrodible and at the same time present an attractive appearance. The machine is somewhat in the form of a 75 cabinet having a bottom wall 1, a front wall 2, end walls 3 and 4, a rear wall 5 and a top wall 6. In parallelism with the end wall 3 and in proximity thereto is a vertical partition 7 providing an operating compartment throughout the height of the machine, and the partition 7 and walls 2, 3 and 5 are connected by a plurality of superposed horizontal partitions 9, said partitions dividing the machine into compartments 10 adapted 80 to contain newspapers or other merchandise to be vended.

The front wall 2 has a door way 11 for each of the compartments 10 and suitably hinged at the upper edge of each doorway 90 is a door 12 that may be easily swung upwardly to permit of easy access to the compartments. The inner side of each door, at the lower edge thereof and contiguous to each end, has keepers 113 adapted to be engaged by hook portions 14 of a latch bar 15 slidable upon the horizontal partition 9 or the bottom of the compartment. Each latch bar is maintained in place by an angle plate 16 having pins 17 extending through longitudinal slots 18 in the latch bar, the pins 17 limiting the longitudinal movement of said latch bar on the partition 9. One end of each latch bar extends through a slot 19 in the partition 7, and is provided with an 100 upstanding bifurcated lug 20 in the operating compartment 8 of the machine.

The front wall 2 of the machine has a

doorway 21 for the operating compartment 8 and said doorway is normally closed by the door 22 hinged adjacent the wall 3 of the machine. The door 22 is adapted to be held closed by a conventional form of lock 23 and on the inner side of the door is mounted a coin controlled operating mechanism which does not interfere with the opening of the door.

10 For each latch bar 15 there is an individual coin controlled operating mechanism on the back or inner side of the door 22, each consisting of a vertically disposed pivoted member 24 having a depending arm 25 provided with a stud 26 adapted to engage in the bifurcated lug 20 of the latch bar 15. The bifurcated lug 20 is engaged by a spring 27 carried by the partition 7, said spring holding the latch bar 15 normally in engagement with the keepers 13 of the door 12, so that the latch bar will be positioned to permit of the stud 26 moving out of the bifurcated lug 20, when the door 22 is swung open.

15 The lower end of the arm 25 is beveled or provided with a tooth 28 adapted to engage in a notch in the upper edge of a pivoted spring pressed pawl 30 carried by the inner side of the door 22. The pawl 30 will yield when the member 24 is actuated to shift the

20 latch bar 15 to an unlocked position to release the door 12 and the end of said pawl will engage the beveled or toothed end of the arm 25 and hold the member 24 in its shifted position, so that the latch bar 15 will be held while the door 12 is opened.

25 The spring 27 engaging the bifurcated lug 20 and lug engaging the stud 26 of the member 4, tends to hold said member in its normal position against a stop 31 carried

30 by the inner side of the door 22. The member 24 has a lateral beveled extension 32 extending into a slot 33 of a coin chute 34 connected to the inner side of the door 22. The coin chute 34 extends in proximity to the

35 bottom of the operating compartment 8 and said coin chute has branches 35 for the individual coin controlled operating mechanism for each of the compartments 10 of the machine. The upper end of the coin chute 34, as well as the branches thereof, has a funnel shaped mouth to receive a coin and a portion of the chute mouth is in communication with a slot 37 in the door 22. The bottom wall of the coin slot 37 is in a

40 horizontal plane with a ledge or rest member 38 connected to the outer side of the door 22, and extending through the slot 37 is the outer apertured end 39 of a push or coin transferring member 40 pivoted on a

45 bracket 41 carried by the inner side of the door 22. The coin transferring member 40 is pivoted by a pin 42 supporting a spring 43 which has one end thereof engaging a post 44 of the member 40, said spring holding the member 40 normally in an extended

position on the rest member 38 so that a coin may be placed in the aperture of the coin transferring member.

The door 22 has a vertical slot 45 in communication with the coin chute 34 adjacent the slot 33 thereof and the slot 45 is also in communication with a slotted guide member 46 secured to the outer side of the door 22 over the slot 45. Slidable in the slotted guide 46 and the slot 45 is a coin actuating member 47 supported normally elevated in the guide member 46 by a coiled compression spring 48. When a coin is placed in the transferring member 40 and said member pushed inwardly, the coin drops into the funnel shaped mouth 36 of the coin chute 34 and is temporarily held by the beveled extension 32 of the pivoted member 24. The coin is below the inner end of the actuating member 47 and when said member is manually depressed or lowered, the coin forces the lateral extension 32 downwardly and said coin is liberated to drop by gravity in the chute 34. The spring 48 will restore the coin actuating member 47 to normal position and the spring 43 will restore the transferring member 40 to normal position, the latter operation taking place immediately upon the member 40 being manually released.

When the pivoted member 24 is tilted or actuated by a coin, the latch bar 15 is shifted to release the door 12, as heretofore pointed out, and to prevent coins from being deposited within the machine when the door 12 is unlocked and the compartment empty, the upper end of the member 24 has an arm 49 that is swung downwardly above the funnel shaped mouth 36 of the coin chute 34. The arm 49 will be in a plane with the rest member 38 and will maintain a coin in the transferring member 40 when said member is forced inwardly. The coin will rest on the arm 49 and be prevented from dropping into the mouth of the coin chute. That side of the member 24 confronting the back or inner side of the door 22 has a suitable designation, as the word "empty" which is adapted to be displayed through a slot 50 in the door 22, such display taking place after the pawl 30 holds the member 24 with the door 12 unlocked, whereby a prospective purchaser of a newspaper or merchandise can readily observe which compartments of the machine are empty.

When the compartments 10 have been loaded and the door 12 closed, the latch bars are released by the opening of the door 22 and the coin controlled operating mechanism is restored to normal position.

The vending machine includes certain other features for the benefit of subscribers, among which may be mentioned audible and visible signals to indicate that "extra" newspapers are for sale. Batteries or a suitable source of electrical energy, generally

designated 51 are adapted to supply electricity to an audible signal 52, as a bell or a visible signal 53 as a red incandescent lamp. A conventional form of electric switch will 5 control the operation of said signals, the bell 52 being used in the daytime and the lamp 53 at night.

What I claim is:—

1. In a vending machine, a cabinet having vertical and horizontal partitions providing operating and merchandise compartments in said cabinet, hinged doors for the operating and merchandise compartments of said cabinet, latch bars slidable on the partitions forming the bottoms of the merchandise compartments and extending into the operating compartment of the cabinet, keepers carried by the doors of the merchandise compartments and adapted to be engaged 20 by said latch bars, bifurcated lugs on the ends of said latch bars in the operating compartment of said cabinet, pivoted members carried by the inner side of the door of the operating compartment and adapted to engage the bifurcated lugs of said latch bars, means normally engaging said pivoted members adapted to hold said members when shifted to retain said latch bars in unlocked positions, and a coin actuating member carried 25 by the door of said operating compartment for each pivoted member, and adapted through the medium of a coin to shift its pivoted member.

2. A vending machine of the type described comprising a cabinet having vertical and horizontal partitions dividing the cabinet into operating and merchandise compartments, doors for all the compartments of the cabinet, latch bars slidable on 30 the horizontal partitions of said cabinet and adapted for locking the doors of the merchandise compartments, said latch bars ex-

tending into the operating compartment of said cabinet and provided with apertured lugs, pivoted members on the door of the 45 operating compartment of said cabinet, and normally engaging the apertured lugs of said latch bars, means engaging said pivoted members adapted to hold said members shifted so that said latch bars are in unlocked 50 position, means carried by the door of the operating compartment of said cabinet adapted through the medium of a coin to actuate each pivoted member, and means carried by each pivoted member adapted to 55 prevent actuation thereof when the latch bar affected by said member is in an unlocked position.

3. In a newspaper vending machine, a cabinet having a newspaper compartment 60 and an operating compartment, doors for both of said compartments, a latch bar in the paper compartment adapted to hold the door thereof closed and said latch bar extending into the operating compartment of said 65 cabinet, a pivoted member carried by the door of the operating compartment of said cabinet, and normally engaging said latch bar, means engaging said pivoted member adapted to hold said member when shifted 70 with the latch bar in an unlocked position, a coin actuating member carried by the door of the operating compartment of said cabinet and adapted through the medium of a coin to shift said pivoted member, and 75 means carried by said pivoted member preventing actuation thereof when said latch bar is in an unlocked position.

In testimony whereof I affix my signature in the presence of two witnesses.
